UNITED STATES PATENT OFFICE.

JOHN BEISWANGER, OF NEW YORK, N. Y.

DESIGN FOR A GLASS CHIMNEY.

SPECIFICATION forming part of Design No. 29,969, dated January 10, 1899.

Application filed December 17, 1898. Serial No. 699,604. Term of patent 14 years.

To all whom it may concern:

Be it known that I, JOHN BEISWANGER, a citizen of the United States, residing in the borough of Manhattan, in the city, county, and 5 State of New York, have invented a new and original Design for a Glass Chimney, of which the following is a specification, reference being had to the accompanying drawing, forming a part thereof.

10 In said drawing the figure is a side elevation of the design.

A is the body portion of the chimney. B is the reduced upper portion thereof. a is the reentering angle at the junction of the parts

15 A and B, and b is the concave contour of the part B above said angle a.

The leading feature of my design is the reentering angle a, where the parts A and B join, and the concave contour at b of the part B above said angle. 20

What I claim is—

The design for a glass chimney, substantially as herein shown and described.

In witness whereof I have hereunto signed my name, this 28th day of November, 1898, in 25 the presence of two subscribing witnesses.

JOHN BEISWANGER.
